UNITED STATES PATENT OFFICE.

ALEXANDER KATZ, OF NEW YORK, N. Y.

CLOTHES-WASHER.

1,105,978.

Specification of Letters Patent.

Patented Aug. 4, 1914.

Application filed October 11, 1913. Serial No. 794,581.

To all whom it may concern:

Be it known that I, ALEXANDER KATZ, a subject of the Czar of Russia, residing in New York, borough of Brooklyn, in the State of New York, have invented certain new and useful Improvements in Clothes-Washers, of which the following is a specification.

This invention relates to devices for use in washing clothing or other materials, and the object of the invention is to provide a device of this class whereby the clothing may be rapidly and thoroughly cleansed. For this purpose means are provided for agitating the water and the clothing said means comprising a hollow conical body adapted to be placed beneath the surface of the water and to be surrounded by the clothing, and means for exhausting air from said body above the surface of the water therein, whereby air from the outside atmosphere is drawn into the body below the water level and the water therein agitated, said agitation extending to the water and the clothing outside of said conical body, so as to assist in cleansing the clothing.

In the accompanying drawings, which show one embodiment of the invention, Figure 1 is a front-view of the device in position in a laundry-tub, the front wall of the tub being removed so that the device may be plainly seen, Fig. 2 is a top-view of the device, Fig. 3 is a vertical central section through the same, Figs. 4, 5, 6, 7 and 8 are views of the regulator for controlling admission of air to the conical body of the device, drawn on a larger scale than the preceding figures, and Fig. 9 is a vertical central section on a larger scale of the injector for withdrawing air from the conical body.

Similar reference numerals indicate corresponding parts in all the figures.

The body 10 of the washer is of generally conical form, as shown, and is provided with a perforated foot-ring or base 11 whereby the lower edge of the cone is raised from the bottom 12 of the tub in which the device is placed. From the top of the cone extends upwardly a neck 13, which is bent at an angle and connects with an injector which comprises a pressure-tube 14, a suction-tube 15, said tubes delivering to a combining-nozzle 16, and a discharge-tube 17 beyond the nozzle. A coupling 18 is connected by a nipple 19 with the neck 13, and is screw-threaded at its opposite end into connection

with the suction-tube 15. In the end of the suction-tube, within the coupling 18, is screwed a removable plug 20, having a bore 21 of small diameter, for limiting the stream of air or water sucked off from the cone. A coupling 22 connects the discharge-tube 17 with an outlet-pipe 23, 24, which latter is connected by a suitable coupling 25 with the waste-pipe 26 at the bottom of the tub. Within the cone is arranged a perforated horizontal partition, for strengthening the cone and for increasing the agitation of the water due to the entrance of air below the partition. Air is permitted to enter the cone through a regulator comprising a vertical tube 30 connected at its lower end with the cone immediately below the partition 27, and provided at its upper end with a cap 31 having depending wings 32 spaced apart and frictionally retaining the cap on the tube. The tube at its upper end is provided with diametrically opposite recesses 28, adapted to be closed by the wings when the cap is turned in the tube with the wings in juxtaposition to the recesses, but when the cap is turned so as to present to the recesses the spaces 29 between the wings, then air passes through said spaces and the recesses 28 to the interior of the tube and thence to the interior of the cone.

The tub is first filled with hot water from the faucet 33, and with the clothing to be washed, the water level being kept below the cap 31. Any suitable coupling 34 may be employed for attaching the injector to the cold water faucet 35. Cold water is now turned on, and the same passes through the injector and the outlet-pipe and waste-pipe 26. In case the cap of the regulator be turned so as to admit air, then the air enters the water below the partition, passes along and through the perforations of the same, and upwardly through the neck 13 and the suction-pipe of the injector, and is carried out with the cold water to the waste-pipe 26. The entrance and passage of the air in the water in the cone agitates the water therein, and this agitation spreads to the remainder of the water in the cone, and to the water outside of the cone, in contact with the clothing in the tub, until the whole becomes an agitated, vibrating mass. When water already near the boiling point is used, the reduction of pressure in the cone brings the water to a boil therein. The degree of agitation is controlled by turning the regulator

cap more or less. The water being thus agitated in contact with the clothing, results in an effective loosening of the dirt from the clothing. If the regulator be almost closed 5 or entirely closed, the suction of the injector is sufficient to draw water from the vertical portion of the neck 13 into the injector, and after this occurs the water is continuously sucked off through the cone and the neck 13 10 until the suction necessary to lift the water the increased distance caused by the lowering of the water level in the tub, is greater than can be furnished by the injector. In case the injector be sufficiently powerful, the 15 suction of water continues until the water-level is reduced to the lower edge of the cone and air enters through the perforations of the base, thus breaking the vacuum.

The cone and other parts of the washing 20 apparatus are preferably made of zinc or other material not injuriously affected by the alkalis used in washing. The outlet-pipe is made in two sections, the upper section fitting frictionally into the lower section 25 24, thus providing an adjustment for length. The plug 20 being removable, permits ready exchange for one having a bore of different size, and thereby the action of the injector may be controlled as desired.

30 The device described provides a simple and convenient means of effectively washing clothing. It enables the use of extremely hot water, inasmuch as none of the parts are liable to be destroyed thereby, and there 35 is no necessity for the user placing the hands in the water. The hot-water faucet is left free at all times for the supply of additional quantities of water when necessary. The device is easily placed in position for use, and

detached when not required, and forms a 40 valuable adjunct to the laundry.

One embodiment of the invention has been shown and described, but it is obvious that changes may be made therein without departing from the spirit of the invention. 45

I claim:

1. A clothes-washer, comprising a hollow body having a perforated base, an injector connected with the top of said body above the water level therein for drawing air and water therefrom, an outlet-pipe connected with said injector and means for admitting air to said body below the water level therein. 50

2. A clothes-washer, comprising a hollow conical body having a perforated base, an injector connected with the top of said conical body; an outlet-pipe connected with said injector, and an air-inlet regulator communicating with the interior of said conical body. 55

3. A clothes-washer, comprising a hollow conical body having a perforated base, an injector connected with the top of said conical body, a perforated partition in the conical body between the base and the top of the same, and an air-inlet regulator communicating with the interior of the conical body 65 below the partition and extending upwardly at the outside of said body above the plane 70 of the top of the same.

In testimony that I claim the foregoing as my invention, I have signed my name in presence of two subscribing witnesses.

ALEXANDER KATZ.
